UNITED STATES PATENT OFFICE.

PAUL HAMILTON, OF GREENSBURG, INDIANA, ASSIGNOR TO JAY V. WESCOTT, OF CHICAGO, ILLINOIS.

TRACK GUARD RAIL.

Application filed March 20, 1924. Serial No. 700,593.

To all whom it may concern:

Be it known that I, PAUL HAMILTON, a citizen of the United States, residing in Greensburg, in the county of Decatur and State of Indiana, have invented a certain new and useful Improvement in Track Guard Rails, of which the following is a full, clear, concise, and exact description, reference being had to the accompanying drawing, forming a part of the specification.

My invention relates particularly to track guard rails which are applied to the traffic rails of a railway opposite the switch frogs although not limited to this use alone.

The main object of the invention resides in the provision of a track guard rail which is light and strong, easily installed, and which is well adapted for its purpose, due provision being made for securing the guard rail.

With this object in view my invention consists in certain features of novelty in the construction, combination, and arrangement of parts by which the said objects and certain other objects, hereinafter appearing, are effected all as fully described with reference to the accompanying drawing and more particularly pointed out in the claims.

In the said drawing—

Figure 1 is a top plan view of the track guard rail of my invention in its applied position with respect to a section of a traffic rail.

Figure 2 is a side elevation of the track guard rail in its applied position with respect to a section of a traffic rail and the ties of a track structure.

Figure 3 is a section on the line 3—3 of Fig. 1.

Figure 4 is a section of the track guard rail on the line 4—4 of Fig. 2.

Figure 5 is an end view of the track guard rail and showing a traffic rail section in proper relation therewith.

Like characters of reference indicate like parts in the various views.

Referring to the drawings the main or body portion of the guard rail is of acute angle cross section, one leg 1 of which angle section forms a base, and the other leg 2 of which angle section extends upwardly from the base and toward a traffic rail 3 to which the guard rail is applied and has a

wheel flange bearing surface 4 along its upper edge facing the head 5 of the traffic rail 3. The base 1 is provided at the ends thereof and at intervals therebetween with downwardly offset portions 6 adapted to overlie respective ties 7 of a track structure, and lateral extensions 8 extend from the portions 6 in both directions and are adapted to underlie the traffic rail to which the guard rail is applied on the one side of the body portion and form wear plates therefor. These extensions are provided with spike apertures 9 whereby the extensions are spiked respectively with the ties and with the traffic rail and ties, apertures of the extensions underlying the traffic rail being disposed adjacent the outer ends of these extensions so that the traffic rail is spiked on the side thereof opposite that on which the body portion of the guard rail lies and the spike apertures thereof including usual stepped spike apertures for the accommodation of traffic rails having base webs of different width. Transverse ribs 10 bridge the angle section of the body portion at intervals in the length thereof and comprise ribs at said downwardly offset portions 6 and therebetween to secure the legs 1 and 2 of the angle section of the body portion firmly, certain of these ribs, i. e., those disposed between the portions 6 being provided with extensions 11 which project outwardly from the main or body portion of the guard rail and engage the web of the traffic rail and under the head thereof for properly positioning the guard rail with respect to the traffic rail and for resisting tipping of the guard rail. Additional transverse ribs 12 are provided on the outside of the leg 2 of the angle section of the body portion and join this leg with the extensions 8 extending outwardly from the corresponding side of the body portion to secure these extensions with the body portion firmly.

The upper portions of the leg 2 adjacent the ends thereof gradually turn away from the traffic rail and slant downwardly toward said ends, as designated at 13, and form relatively low vertical end portions as designated at 14. Laterally projecting formations, consisting of horizontal top portions 15 connected with the leg 2 of the body portion thereof and vertical end wall portions 16 connected with the leg 2 at the extreme ends thereof and with the top por-

tions 15, are formed at the ends of the body and project toward the traffic rail to which the guard rail is applied and are adapted to engage in the opposing channel of the traffic rail thereof to aid in the securing of the guard rail in proper relation with the traffic rail, these formations serving for properly positioning the guard rail with respect to the traffic rail and forming a strong and light boxlike depth guard structure at the ends of the guard rail.

It will be observed that the portions of the leg 1 of the body portion between the portions 6 thereof are disposed above the tie 15 and roadbed level thereby providing against clogging, and these portions of the leg 1 are provided with apertures 17 which also aid in providing against clogging and in addition reduce the weight of the guard rail 20 without undue sacrifice of strength.

Thus it will be observed that a light and strong structure is provided which is well adapted to withstand the strains and stresses incidental to use.

25 While I have herein shown and particularly described the preferred embodiment of my invention I do not wish to be limited to the precise details of construction shown as changes may readily be made without departing from the spirit of my invention, but having thus described my invention I claim 30 as new and desire to secure by Letters Patent the following:—

Claims:

35 1. In a track guard rail the combination of a base portion, a guard portion extending along said base and disposed at its intermediate portion at an acute angle with the base and extending upwardly toward a traffic rail to which the guard rail is applied and having the upper portions thereof adjacent the ends thereof gradually turned away from the traffic rail and forming vertical end portions, transverse ribs bridging 40 said angle of the base and guard portion at intervals along the intermediate portion of said guard portion and extended therefrom toward the traffic rail to engage the same under the head thereof, and depth guard formations at the ends of said guard portion and extending therefrom toward the traffic rail and adapted to engage the same under the head thereof.

2. In a track guard rail the combination 45 of a base portion provided with lateral extensions spaced therealong forming wear plates, a guard portion extending along said base and disposed at its intermediate portion at an acute angle with the base and ex-

tending upwardly toward a traffic rail to which the guard rail is applied and having the upper portions thereof adjacent its ends gradually turned away from the traffic rail and forming vertical end portions, transverse ribs at said extensions disposed 55 at said intermediate portion of said guard portion and bridging the said angle of the base and guard portion, additional transverse ribs disposed between said extensions at said intermediate portion of the guard 60 portion and bridging said angle of the base and guard portion and extended therefrom toward the traffic rail to engage the same under the head thereof, and depth guard formations at the ends of said guard portion 65 consisting of horizontal top portions connected with said guard portion and vertical portions connected with said guard portion and respective of said top portions underneath the same, said depth guard formations extending from said guard portion toward the traffic rail and adapted to engage the same under the head thereof.

3. In a track guard rail the combination 70 of a base portion provided with lateral extensions spaced therealong and extending from both sides thereof forming wear plates, a guard portion extending along said base and disposed at its intermediate portion at an acute angle with the base and extending 75 upwardly toward a traffic rail to which the guard rail is applied and having the upper portions thereof adjacent its ends gradually turned away from the traffic rail and slanted downwardly toward said ends and forming 80 relatively low vertical end portions, transverse ribs at said extensions on both sides of the guard portion bridging both angles of the base and guard portion, transverse ribs disposed between said extensions at said 85 intermediate portion of the guard portion and bridging said acute angle of said base and guard portion and extended therefrom toward the traffic rail to engage the same under the head thereof, and depth guard 90 formations at the ends of said guard portion 95 consisting of horizontal top portions connected with said guard portion and vertical portions connected with said guard portion and respective of said top portions underneath the same, said depth guard formations extending from said guard portion toward the traffic rail and adapted to engage the same under the head thereof.

In witness whereof I hereunto affix my 100 signature this 3rd day of March, 1924.

PAUL HAMILTON
